MAGNETIC CAR RETARDER

Ned C. L. Brown, Scottsville, N. Y., assignor to
General Railway Signal Company, Rochester,
N. Y.

Application November 25, 1931, Serial No. 577,225

10 Claims. (Cl. 188—62)

This invention relates in general to car retarders of the track brake type, and has more particular reference to a magnetically operated car retarder.

5 It is desirable, in car retarders, to provide as high an intensity of retardation as is possible, and furthermore to provide means for compensating for variations in the spacing of car wheels on their axles.

10 More specifically, in order to provide a high intensity of retardation, it is proposed to provide means whereby brake shoes, when applied to passing car wheels, are raised so as to contact with the wheels at as high a point as clearance conditions on the car will permit, and since the usual clearances for locomotives are less than for cars, means is provided for permitting the shoes to be pushed downwardly upon the passing of a locomotive.

15 Furthermore, to care for the variations in spacing of car wheels on their axles, the magnetic actuating means for the retarder is floatingly supported.

20 Further objects, purposes and characteristic features of this invention will appear as the description progresses, reference being made to the accompanying drawing showing, solely for the purpose of illustration, and in no manner in a limiting sense, one form which the invention can 25 assume.

In the drawing:—

Fig. 1 is a plan view of an embodiment of the invention.

Fig. 2 is a sectional view on line 2—2 of Fig. 35 1, viewed in the direction of the arrows.

Fig. 3 is a sectional view on line 3—3 of Fig. 1, viewed in the direction of the arrows.

Fig. 4 is a sectional view on line 4—4 of Fig. 40 5, viewed in the direction of the arrows.

Fig. 5 is a sectional view on line 5—5 of Fig. 45 1, viewed in the direction of the arrows.

Referring now to the drawing, there is here shown usual ties 1, carrying track rails 2, one only of which is shown. Positioned at each side 45 of each track rail, is a brake shoe beam 3, carrying a brake shoe 4, attached thereto in any usual manner, as for example, in application Ser. No. 464,892 filed June 30, 1930.

Below the track rail 2 at intervals, are pairs 50 of core members 6, formed if desired by threaded members 7, as shown in Fig. 2, to form supports on which are carried energizing windings 8, which can be energized electrically, in any usual or desired manner. These core members 6 have 55 their pole shoes tilted from the vertical, in an

outward direction, to form an angle with the web of the rail, thereby to tilt the brake beams 3, as shown in Fig. 2, to raise the brake shoes 4, when the beams 3 are in attracted position, as shown in Fig. 2. The shoe beams 3 are thus releasably held in braking position by the pole shoes 6, subject of course to being broken free from the shoes, if sufficient force be exerted, without breaking any of the parts and thus, what can aptly be termed a break-down connection exists between these parts.

5 At suitable spaced intervals are compression springs 9, anchored on lugs, for example, as 10 and 11, and operating to bias the brake beams 3, and brake shoes 4, away from the track rail, 15 to move the beams and shoes away from the track rails when the windings 8 are de-energized.

The brake beams are articulated, as at 12, as in the above referred to application, for example, and are slidable toward, and away from, the 20 track rail in chairs C, which are bolted to the ties beneath the ends of the separate brake beams, such as wood or non-magnetic I beam ties 14, by bolts or the like 15. These chairs, as shown particularly in Figs. 4 and 5, each has a base 25 15', and a head 16 spaced therefrom, to provide slots 17 and 18.

At each end of each brake beam section, are projecting lugs 19 and 20, received respectively in the slots 17 and 18, and slidable therein as 30 the shoe beam is moved toward, and away from, the track rail. The slot 18 expands outwardly to allow the lug 20, on the shoe beam, when the shoe beam is moved away from the track rail, to move upwardly, and thereby permit the front 35 edge of the shoe beam, and its carried brake shoe to move downwardly.

The entire magnetic structure, comprising the windings 8, the cores 6 and member 7, is carried on rollers or the like 21, mounted on trunnions 22, 40 whereby it can move laterally of and, free from, the track rail, on support means 23, preferably non-magnetic.

It will thus be apparent from the above, that, 45 with windings 8 de-energized, springs 9 move the brake beams and brake shoes away from the track rails 2 to permit the lugs 19 to drop to the bottom of slots 17, and the lugs 20 to raise upwardly into the upper portion of the inwardly tapered slots 18. Thus, in de-energized position, the brake shoes are moved away from, and downwardly of, the track rails.

50 On energizing the windings 8, the pole shoes of cores 6, attract the brake beams and pull them 55

inwardly so as to position the brake beams against the pole shoes and thereby raise the brake shoes upwardly, to apply them to passing wheels at as high a point as the clearance diagram of the cars will permit. A passing locomotive with less clearance than the energized retarder normally affords, will simply push the brake shoes and shoe beams downwardly and outwardly, opening the break-down connection between the shoe beams, until it passes by, whereupon the parts will return to the position shown in Fig. 2, to produce a high degree of retardation due to the shoe being applied to the wheel at a relatively great distance in from the wheel periphery.

The floating support for the magnetic operating structure, comprising the rollers 21, permits the magnetic structure to shift from side to side to care for variations in spacing of wheels on the axles. For example, should the wheels be more closely spaced than normal this would result in moving one of the brake beams and brake shoes away from its usual position, when in retarding position, to thereby leave a considerable air gap between the lower part of one of its brake beams and its respective magnetic pole shoe, to thereby weaken the effect of the magnetic operating means. The other brake beam for this wheel, under such conditions, might be against its respective pole piece, and still not have its brake shoe in tight contact with the car wheel. The floating supports for the magnetic structures permit them to readily shift from side to side and center them under the car wheels, regardless of the spacing of the car wheels on the axles, within such limits as encountered in practice.

It is of course understood, that the number, per length of retarder, of magnetic elements, such as shown in Fig. 2, can be varied in accordance with requirements, and the same is true of the separating springs 9, the invention not being limited in any manner whatsoever, by the number and distribution and proportions of the various parts involved.

Furthermore, the above rather specific description of one form of the present invention is given solely by way of illustration, and is not intended, in any manner whatsoever, in a limiting sense. Obviously, the invention can assume many different physical forms, and is susceptible of numerous modifications, and all such forms and modifications, are intended to be included by this application, as fall within the scope of the appended claims.

Having described my invention, I now claim:—

1. In a car retarder of the track brake type, in combination, a brake beam, a brake shoe on the brake beam, means for guiding the beam toward and away from a track rail, electro-magnetic means for moving the beam toward the rail, and means for movably supporting the magnetic means, whereby to accommodate for variation in wheel spacing on a car axle.

2. In a car retarder of the track brake type, in combination, a brake beam, a brake shoe on the brake beam, means for guiding the beam toward and away from a track rail, electro-magnetic means for moving the beam toward the rail, elastic means biasing the beam away from the rail, and roller means for movably supporting the magnetic means whereby to accommodate for variation in the spacing of wheels on a car axle.

3. In a car retarder of the track brake type, in combination, a brake beam, a brake shoe on the brake beam, means for guiding the beam toward and away from a track rail, electro-magnetic

means for moving the beam toward the rail, means for movably supporting the magnetic means, whereby to accommodate for variation in wheel spacing on a car axle, and means whereby the magnetic means raises the beam when moving it toward the rail.

4. In a car retarder of the track brake type, in combination, a brake beam, a brake shoe on the brake beam, means for guiding the beam toward and away from a track rail, electro-magnetic means for moving the beam toward the rail, means for movably supporting the magnetic means whereby to accommodate for variation in wheel spacing on a car axle, and means whereby the magnetic means releasably raises the beam when moving it toward the rail whereby to accommodate for variations in clearances of passing vehicles.

5. In a car retarder of the track brake type, in combination, a brake beam carrying a brake shoe, means for guiding the beam toward and away from a track rail, electro-magnetic means for moving the beam toward the rail, and a pole shoe in the magnetic means so positioned as to cause the beam to raise as it is moved toward the rail.

6. In a car retarder of the track brake type, in combination, a brake beam carrying a brake shoe, means for guiding the beam toward and away from a track rail, electro-magnetic means for moving the beam toward the rail, and a pole shoe in the magnetic means positioned out of parallelism with the rail and cooperating with a portion of the beam so as to raise the beam as it is moved toward the rail.

7. In a car retarder of the track brake type, in combination, a brake beam carrying a brake shoe, a slotted chair means for guiding the beam toward and away from a track rail, lug means on the beam receivable in the slot of the chair, electro-magnetic means for moving the beam toward the rail, and a pole shoe in the magnetic means positioned so as to cause the beam to raise as it is moved toward the rail.

8. In a car retarder of the track brake type, in combination, a brake beam, a brake shoe on the brake beam, means for guiding the beam toward and away from a track rail, operating means for moving the beam toward the rail, and means whereby the operating means raises the beam, on a break-down connection, when moving it toward the rail.

9. In a car retarder of the track brake type, in combination, a brake beam, a brake shoe on the brake beam, means for guiding the beam toward and away from a track rail, operating means for moving the beam toward the rail, means for movably supporting the operating means whereby to accommodate for variation in wheel spacing on a car axle, and means whereby the operating means releasably raises the beam when moving it toward the rail whereby to accommodate for variations in clearances of passing vehicles.

10. In a car retarder of the track brake type, in combination, a brake beam carrying a brake shoe, a slotted chair means for guiding the beam toward and away from a track rail, lug means on the beam receivable in the slot of the chair, operating means separate from, and bodily movable relatively to, the chair, for moving the beam toward the rail, and causing the beam to raise as it is moved toward the rail.
